HAY CARRIER.

No. 288,839.

Patented Nov. 20, 1883.

UNITED STATES PATENT OFFICE.

RICHARD MILLER, OF APPLETON, WISCONSIN, ASSIGNOR OF ONE-HALF TO
JOHN G. KANOUSE, OF SAME PLACE.

HAY-CARRIER.

SPECIFICATION forming part of Letters Patent No. 288,839, dated November 20, 1883.

Application filed April 5, 1883. (No model.)

To all whom it may concern:

Be it known that I, RICHARD MILLER, a citizen of the United States of America, residing at Appleton, in the county of Outagamie 5 and State of Wisconsin, have invented certain new and useful Improvements in Hay-Carriers; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 This invention relates to a reversible hay-carrier, designed especially for transferring hay from wagons to the hay mow or bin of a barn, but which may also obviously be used for transferring loads from wagons in various 20 places.

The object of my invention is to provide a strong, durable, and easily-operated implement of this class which may be readily reversed, so as to be operated from opposite directions, and which will be automatically locked and unlocked at the points for loading and unloading.

The invention consists in certain novel constructions and combinations of devices, which 30 will be hereinafter particularly described, and pointed out in the appended claims.

In the accompanying drawings, Figure 1 is a side elevation of my improved hay-carrying apparatus as when traveling with its load 35 locked in an elevated position. Fig. 2 is a similar view of the apparatus with the carriage locked and the raising and lowering devices free. Fig. 3 is an end view of the carriage with the rail in section. Fig. 4 is a longitudinal section of the carriage and rail, and 40 Fig. 5 is a detail perspective view.

The letter A designates a rail upon which the carriage is to run, and which is to be suitably supported in a barn or other building 45 where loads are to be transferred from wagons or from place to place.

The letters B B are two inverted arch-shaped parallel bars having their upper ends extending above the rail, and provided with 50 wheels C C, which run upon the upper surface

of said rail. The lower curved portions of these bars extend below the rail, and are provided on their inner surfaces with downwardly-projecting lugs d d, to which is secured a circular collar, E, having at its lower edge an 55 outwardly-projecting flange, e.

F F are the two side bars forming the supporting-frame of the raising and lowering devices. These bars have depending ends f, and are bent at their middle portions, as shown at 60 g, to form the two halves of a swiveling band which embraces and turns freely upon the collar E and its flange e when the two side bars are connected together by short connecting-pins h.

65 Between the two depending ends of the bars F on one side of the band E is pivoted a pulley, I, and between said side bars on the other side of the band is pivoted a locking-lever, K, the lower portion of which is curved inwardly, 70 and provided with an eye, k, at its end, while the upper portion extends through a slot in a horizontal sliding bar, L, lying between the side bars directly under the flange e, and supported by two of the cross-pins which connect 75 the side bars. This sliding bar L has at about its middle an opening to receive the locking-pin m of a vertically-sliding latch, M, which is provided with two upwardly-projecting and inwardly-overhanging fingers, m'.

80 The letter N indicates an arched plate arranged under the rail A, and secured at a proper distance therefrom by short arms n, which are much narrower than the plate, in order that said plate may project laterally on 85 each side.

When the latch M is in its lowermost position, it rests upon the sliding bar L, and its pin extends into the opening thereof, and in this position of the latch its overhanging fingers m' are in position to catch over the lower ends of the arched plate N when the carriage is running on the rail, and as the carriage progresses after their engagement with said plate said fingers will ride upward on the plate and 90 raise the latch, so that its pin will be withdrawn from the hole in the sliding bar.

95 The letter O indicates an operating-rope, which has one end secured to a strap, o, behind the locking-lever K, and said rope ex- 100

tends along the back of the lower curved portion of said lever, through its eye *k*, downward around a loose pulley, *P*, which is provided with a hook, *p*, and upward over the pulley *I*, from whence it extends along under the rail and over an adjustable, removable, and replaceable pulley, from whence it depends in convenient position to be operated.

The operation of my invention as now described is as follows: The rail is to be provided preferably with two of the arched plates *N*, one being located over the point of loading and the other over the point of unloading the carrier. The carriage being in the position indicated in Fig. 2, the latch *M* is elevated by the engagement of its overhanging fingers with the arched plate *N*, and its pin is disengaged from the sliding bar *L*. Therefore the weight of the pulley *P*, operating through the cord *O*, swings the locking-lever *K* so that it will slide said sliding bar to project outwardly over the pulley *I*. In this position of the parts the rope is to be relaxed and the pulley *P* allowed to descend and be engaged with a sling carrying hay, or with any other load which it is desired to transfer. When it is engaged, it is drawn upward by means of the cord *O*, and the pulley *P* rides upward upon the inner side of the lower curved portion of the locking-lever *K*, the lower end of said locking-lever being then drawn upward and inward, so that its upper end is swung outward and slides the sliding bar *L* so that its middle opening or hole comes directly under the pin of the latch, the sliding bar being stopped in this position by means of a catch, *l*, formed at its end to engage with one of its supporting-pins. The carriage now being drawn along the rail by means of the rope, the latch escapes from the arched plate and falls with its pin in the opening of said sliding bar, which thus holds the locking-lever *K* in position to support the pulley *P* in its elevated position, so that the load suspended by said pulley cannot descend, which position of the parts is illustrated in Fig. 1. When, now, the carriage has reached the point where the load is to be delivered, and the latch engages with the arched plate at that point, disengaging its pin from the hole in the sliding bar, the rope is to be relaxed and the weight of the load swings down the locking-lever *K*, so that it slides the sliding bar *L* out over the pulley *I*, as shown in Fig. 2, with its opening or hole out of coincidence with the latch-pin. Now, a slight further movement of the carriage beyond the center of the arched plate causes said plate to drive the latch downward, so that its pin will impinge upon the upper surface of the sliding bar, and thus the carriage will be locked, so that it cannot move away from the arched plate in either direction until the pulley *P* is again raised and the locking-lever *K* swung into po-

sition, as shown in Fig. 1. When the carriage has been run to any point, and it is desired to then run it in the reverse direction, the pulley *Q* is detached from its original position and secured to the rail at a point on the opposite side of the carriage. The bars *F* and band *g* may be swung around on the collar *E* and its flange *e*, thus bringing the free end of the rope in proper position for the carriage to be drawn in the desired direction. It is not absolutely necessary to use a third pulley, as the rope may be operated by passing it down directly over the pulley *I*; but a third or stationary pulley is convenient for allowing the operator to stand off at a considerable distance in operating the carriage. Said pulley may be suspended from a grapple, which may be readily engaged and disengaged with the rail, as desired.

Having now fully described my invention and explained the operation thereof, what I claim is—

1. The combination, with the side bars of the carriage and the flanged collar *E*, secured thereto, of the band *g*, swiveled upon said collar, and having the downward-projecting arms *f*, the pulley *I*, pivoted to the depending arms *g* on one side of the band, the locking-lever *K*, pivoted to said arms on the other side of the band, the sliding bar *L*, engaged with said locking-lever, and a suitable latch for engaging said sliding bar, substantially as described.

2. The combination, with the rail provided with the arched plate *N*, of the carriage provided with the flanged collar *E*, the frame swiveled upon said collar, the sliding bar *L*, having an intermediate opening and arranged below the flange of said collar, the latch *M*, adapted to be operated by the arched plate, and provided with a pin for engaging said sliding bar, the pivoted locking-lever having its upper end engaged with said sliding bar and its lower end curved inwardly, the pulley *I*, the loose pulley *P*, and the cord *O*, engaged with the lower end of said locking-bar, substantially as described.

3. The combination, with the swiveling frame for supporting the raising and lowering devices, and the carriage provided with the flanged collar for supporting said swiveling frame, of the sliding bar *L*, supported by said frame, the vertically-moving latch *M*, provided with the overhanging fingers *m'*, and the rail provided with the arched plate *N*, for engaging and operating the latch, substantially as described.

In testimony whereof I affix my signature in presence of two witnesses.

RICHARD MILLER.
